UNITED STATES PATENT OFFICE.

GEORGE W. MANNING, OF CHICAGO, ILLINOIS.

BROOM-TRIMMING MACHINE AND METHOD.

1,381,927.

Specification of Letters Patent. Patented June 21, 1921.

Application filed March 8, 1919. Serial No. 281,331.

To all whom it may concern:

Be it known that I, GEORGE W. MANNING, a citizen of the United States, and resident of Chicago, in the county of Cook and State 5 of Illinois, have invented certain new and useful Improvements in Broom-Trimming Machines and Methods, of which the following is a specification.

This invention relates to broom-trimming machines and methods and has for its primary object the provision of an improved machine for trimming to equal length by one stroke of a knife the bristles on opposite sides of a broom while trimming the 15 bristles of the central portion somewhat shorter to slightly concave the foot of the broom along a line transverse to the general plane defined by the broom.

Further objects are: to provide an improved method of trimming:

To provide improved means for simultaneously trimming the foot and shoulders of a broom:

To provide improved means for supporting the waste ends to be trimmed from a broom during the cutting movement of the knife:

To provide novel means for preventing lateral movement of the bristles under the 30 action of the knife:

To provide an improved knife shaped to prevent spreading of bristles at the end of its cutting stroke:

To provide improved means for holding 35 a broom against shifting and tilting under the force of shoulder trimming blades:

To provide improved shoulder trimming blades shaped and arranged to draw the edge bristles of a broom inward against the 40 body of bristles during the trimming of the shoulders:

To provide an improved machine for simultaneously trimming the foot and shoulders of a broom and adjustable to handle 45 various lengths and widths of brooms:

To provide improved means coöoperating with the clamps of a broom for trimming bristles projecting from between the clamps:

To provide improved means for centering 50 a broom with relation to apparatus for holding and trimming it:

To provide improved means for guiding a broom into holding and trimming apparatus: and

To provide improved means for loosening 55 a broom from supporting elements upon which it has been pressed.

Other objects and advantages of the invention will appear from the following description, taken in conjunction with the accompanying drawings which form a part of this specification and illustrate the preferred embodiment of the invention.

In the drawings:

Figure 1 is a front elevation of the invention. 65

Fig. 2 is a top plan view thereof.

Fig. 3 is a bottom plan view of the die plate of the machine showing the devices carried thereby. 70

Fig. 4 is a top plan view of the base plate of the machine showing the elements mounted thereon.

Fig. 5 is a longitudinal vertical section taken approximately on line 5—5 of Fig. 2. 75

Fig. 6 is an end elevation of the machine taken from the right hand end of Fig. 1.

Fig. 7 is a transverse vertical section taken on line 7—7 of Fig. 1.

Fig. 8 is a plan view of the upper side of 80 a clamp broom which the present invention is adapted to trim, illustrating the positions assumed by the waste ends of the edge bristles during the cutting operation and showing in top plan a detent employed in centering the broom in the machine as well as a fragment of a centering arm, stop and sleeve forming part of the present invention. 85

Fig. 9 shows, for purposes of explanation, an improper arrangement of parts for trimming the foot of a broom. 90

Fig. 10 illustrates the uneven trim given to the foot of a broom by the operation depicted in Fig. 9.

Fig. 11 illustrates diagrammatically the 95 arrangement of parts in the present invention for trimming the foot of a broom.

Fig. 12 shows in longitudinal central section the foot of a broom trimmed by the operation of the present invention as depicted 100 in Fig. 11.

Fig. 13 is an edge elevation of the head of a clamp broom centered in and held by the machine of this invention, showing in side elevation part of a centering arm, in 105 section a stop, and sleeve mounted thereon, and in end elevation a head block and presser head.

The frame of my machine comprises a base plate 20 adapted to lie horizontally upon the bed of a power press of any suitable type. Reciprocable vertically toward 5 and from the base plate is a die plate 21 positioned above the base plate and adapted for attachment to the vertically driven head of the power press (not shown) by the provision of any convenient means, such, for 10 example, as the centrally disposed upstanding stud 22. To insure accuracy of movement of the die-plate in a straight line toward and from the base plate, the latter is provided with guide posts 23 and 24, one at 15 each end. These guide posts are rigidly fixed by their lower ends in the base plate, extend vertically therefrom in parallelism, and snugly and slidably engage vertical bearings 25 and 26, respectively, provided 20 in the die plate. The posts are positioned near the back of the machine, as best seen in Figs. 2 and 6, to permit the unobstructed feeding and removal of brooms through the front.

25 Brooms are fed edgewise into and similarly removed from the machine through the front thereof, the flat sides of the brooms being horizontal during the cutting of the bristles as indicated in Fig. 5. In dotted 30 lines in Fig. 4 is shown fragmentarily a trimmed broom being removed from the machine. Figs. 5 and 6 illustrate the position 35 of parts when the cutting of the broom is half completed. In Figs. 1 and 7 the normal position of the parts is shown at that point 40 in the movement of the die plate where the devices it carries are in position to contact with the upper side of a broom; for feeding and removal of brooms from the machine, however, the die plate is elevated farther 45 from the base plate than in Figs. 1 and 7. At the left in Figs. 1, 3, 4, and 5 is shown the group of base plate elements and die plate devices which operate upon the head 50 of a broom; while at the right in these figures is shown the group of elements and devices operating upon the foot thereof. Certain interactions between these two groups of parts will appear from their further description herein.

Figs. 8 and 13 illustrate the clamp broom which certain parts of this invention are designed to hold and trim. This broom comprises a body of bristles, generally indicated 55 at 27, which, just below its head, is sewed as at 28, in the customary manner, and has its bristles bound into a head by opposed clamps 29 and 31 the upper edges of which define the shoulder contour of the finished 60 broom. Opposed shanks, 32 and 33 respectively, project one from each clamp, forming an axial handle socket, the longitudinal axis of the broom being indicated at 34 in Figs. 8, 10, 12, and 13. Various features of 65 my improved machine are, however, adapt-

ed to the trimming of other than clamp brooms.

The head of a broom is supported on the upper horizontal surface 35 of a head block 36 mounted on the base plate near its left 70 end. A foot block 37, having an upper surface 38 for support of the foot of a broom, is mounted near the right hand of the base plate. Surfaces 35 and 38 are in a common 75 horizontal plane. The head and foot blocks extend transversely of the base plate, the foot block being slightly curved from end to end to trim to a convex line the foot of the broom as viewed from one of its flat sides; the foot block at its upper outer 80 corner is formed with a sharp edge 39 co-operating with a knife to trim the foot of a broom. Between the head and foot blocks, and preferably nearer the latter, is mounted transversely of the base plate a platen 41, 85 having its upper horizontal surface 42 positioned below the plane of the broom supporting surfaces 35 and 38 for supporting the medial portion of the broom. The three 90 surfaces 35, 42, and 38 are thus accurately 95 disposed, so that when a broom is pressed against them the bristles of its lower side will be downwardly arched. A large part of the top of the foot block is preferably 100 cut down on the side toward the platen to 105 form a surface 40 in the plane of platen surface 42.

The bristles at the foot of a broom, being unconfined by sewing, wiring, or clamps, spread out to greater thickness and width 110 than at the head. Obviously, therefore, when a broom is laid flatwise on a horizontal surface, the bristles of the lower side will 115 parallel that surface, those in the central portion of the broom will slant upward at a slight angle to the horizontal, and those of the upper side will slant upward at a greater angle. If now a knife be passed vertically across that horizontal surface (the lower bristles remaining substantially horizontal) 120 the knife, in compressing the bristles against the surface to cut them, will decidedly arch the bristles in the central and upper portions of the broom, so that, when the foot is trimmed and the bristles allowed to 125 straighten out, the upper bristles will be decidedly longer than the lower ones. This 130 improper mode of trimming a broom is depicted in Fig. 9 and its result in Fig. 10. In these figures, and in Figs. 11 and 12, the observer views the foot of the broom in section on the axial line 34—34 of Fig. 8. In Fig. 9 the bristles are gradually increased in length from the center to the upper side of the broom, while they are gradually decreased from the center to the lower side, this uneven trim rendering a broom difficult 135 to handle in sweeping. By my improved method and machine the bristles of the upper and lower sides are trimmed to equal 140

lengths and those in the central portion are very slightly shorter to slightly concave the foot of the broom on a line from one flat side of the broom to the other, while, on a line from edge to edge of the broom its foot is convexly trimmed; such a trim being conducive of ease in handling and long life, due to uniform wear. This method is illustrated in Figs. 5 and 11, and its result in Fig. 12, the bristles being of equal length at equal distances in opposite directions from the axis 34. It consists in maintaining the bristles of the central portion substantially straight, arching from each other the bristles on opposite sides of the central bristles, and passing a knife across the foot of the broom at right angles to the central bristles. To this end I provide the die plate with a presser head 43 opposed to the head block 36, a presser foot 44 opposed to foot block 37, and a presser bar 45 opposed to platen 41; these three pressing devices holding the broom against the elements to which they are opposed, during the cutting operation.

The presser head is resiliently carried by the die plate Fig. 5; spaced threaded rods 46, rigidly fixed in the die plate, project upwardly therefrom and are spanned by a yoke 47 movable along the rods and held at any desired level by lock nuts 48. Spaced hangers 49 and 51 traverse vertical bearings provided in the yoke and die plate, being held from dropping through the yoke by pins 52. Springs 53 are interposed between the yoke and a shoulder formed on each hanger to press the hangers normally downwardly in the yoke and die plate, and it is by the force of these springs that the presser head 43—carried on the lower ends of the hangers—is forced against the head of a broom.

The presser foot is resiliently carried by the die plate (Figs. 3 and 5): fastened by their inner ends near the lower surface of the die plate, along the transverse center line thereof, by bolts 54 is a pair of co-extensive spaced, leaf springs 55 extending toward the right hand end of the machine and slanted downwardly; the presser foot 44—carried on their outer ends—being forced against the foot of a broom by the strength of these springs.

The presser bar is resiliently carried by the die plate by a similar arrangement of parts (Figs. 3 and 5): shorter and more steeply slanted leaf springs 56 have their inner ends fastened near the die plate by bolts 54, extend therefrom toward the right hand end of the machine, carry presser bar 45 on their outer ends and force it against the medial portion of a broom lying across platen 41.

In Fig. 9 the highest point of the excessive arch of the upper bristles is numbered 57; it is at this point that presser bar 45 lies across and presses upon the bristles of a broom in my machine, reducing somewhat

the excessive arch of the upper bristles, straightening out the central bristles, and downwardly arching the lower bristles from the level of surfaces 35 and 38 to that of surface 42. Spreading of the bristles under the pressure of bar 45 is prevented by the sewing 28 and certain retaining posts, to be described, positioned at the edges of the broom near its foot.

A foot trimming knife 58 depends vertically from the right hand end of the die plate in position to coöperate with the sharp edge 39 of the foot block—across which it moves—to cut off the waste ends of the broom foot leaving the foot of the finished broom concaved as indicated at 59 in Fig. 12. To slightly convex the foot of the finished broom, foot block 37, presser foot 44 and knife 58 are, in plan view, curved outwardly toward the right hand end of the machine, the resulting curve being shown at 61 in Fig. 8.

An end block 62, (Figs. 1, 4, 5, and 6) curved in conformity with knife 58 and the foot block, traverses the base plate and is spaced sufficiently from the foot block to permit movement of the knife between itself and the foot block. The upper horizontal surface 63 of this end block supports the waste ends to be trimmed by the knife, so that, should the knife wear dull, these ends cannot bend down over edge 39 of the foot block and be merely pinched between the knife and foot block, but are held at substantially right angles to the vertical cutting movement of the knife so that they are cleanly severed. A pair of horizontally disposed pivot arms 64 are formed one on each extremity of the end block, these arms traversing the extremities of the foot block and being co-axially pivoted as at 65 to a portion 66 of the end block extending from the lower portion of the latter toward the center of the machine. Coiled springs 67 have their upper ends embedded in the bottom of the end block near the extremities thereof, and bear at their lower ends on the smooth upper surface of bed plate 20. These springs support surface 63 of the bed plate normally flush with the broom supporting surface 38 of the foot block and yield slightly when, during the cutting of the bristles, a bunch of tough bristles offers unusual resistance to the knife. Mediantly of its extremities the bottom of the end block is cut away as at 68 to prevent collection of waste ends of bristles between the foot and end blocks.

The cutting edge 39 of knife 58 (Figs. 1, 5, and 6) slants upwardly from back to front of the machine, striking first the bristles at the rear edge of the broom and successively cutting the bristles forwardly of that rear edge. To prevent travel of the bristles forwardly of the machine in a horizontal direction between the foot block and presser foot under the slanting edge of the knife,

the broom is impaled on a series of spaced teeth 71 that project upwardly toward the presser foot from the foot block. These teeth are arcuately disposed in conformity 5 with the curve of the foot block, and may rise from the narrow broom supporting surface 38 thereof, though, preferably they rise from the lower surface 40 of the foot block very close to the inner edge of surface 38 10 (Figs. 4 and 5) and cross the plane of the latter. A similar series of spaced teeth 72 projects downwardly toward the foot block from the presser foot, being staggered with respect to teeth 71 and slightly overlying, 15 though out of contact with, the tips of the latter. Teeth 71 and 72 are all preferably shorter than the thickness of the foot of the broom when pressed between the foot block and presser foot. By arresting lateral movement of the bristles, the teeth prevent grouping of the bristles into thick bunches, thereby relieving the knife of undue strain; and they also insure an even trim of the bristles 20 as regards length.

25 The upwardly slanting cutting edge 69 of knife 58 terminates in a sharply down curved cutting hook 73 which, in cutting the bristles at the extreme forward edge of the broom—indicated at 74 in Fig. 6—exerts pressure 30 backwardly and downwardly on them to prevent their bending forwardly and being either unevenly trimmed or merely pinched between the knife and an end retaining post rising from the foot block and 35 to be described. The action of the lower end of knife 58 and its hook 73 in pressing the edge bristles toward the axis of the broom is shown by the full line position of the waste ends to the right of line 61 in Fig. 8; their 40 position before they are cut being indicated in dotted lines.

45 To prevent horizontal spreading of the bristles at the edges of the broom near the foot thereof when it is fed into the machine and during descent of the presser foot a pair of retaining posts 75 and 76 are provided projecting upwardly one from each end of the foot block. These posts are rigidly fixed to the foot block and extend vertically there- 50 from to a height above surface 38 greater than the normal thickness of the foot of an untrimmed broom. They also traverse and stand very close to the ends of the presser foot 44 during its descent and pressure upon 55 the broom.

60 In plan view the left hand or outer side of head block 36 (Figs. 1, 4, 5, and 7) is curved in conformity with the broom shoulder contour defined by the edges of clamps 65 29 and 31. To assist in supporting the heads of the bristles during the shoulder trimming operation the head block is provided with a raised outer rim having a bristle supporting upper surface 77 and a sharp edge 78. The difference between surfaces 35 and 77 of the

head block is equal to the thickness of clamp 29 which lies upon surface 35 and within the raised outer rim. A pair of shoulder trimming blades 79 and 81 depend vertically from the die plate near its left hand end and move 70 across the edge 78 to cut off the waste head ends of the bristles. These blades may conveniently be made of a single piece recessed as at 82 (Figs. 3 and 5) to straddle the shanks 32 and 33. The cutting edges 83 of 75 these blades slant downwardly from their inner to their outer ends and are sharply pitched at the outer lower ends to form hooks 84 positioned above the edge bristles of the broom for pressing the edge bristles inwardly against the body of uncut bristles, thereby securing a clean cutting of the edge bristles on the descent of the blades. The cutting of the bristles at the head 80 of the broom occurs between the sharp edge 78 of the head block and edges 83 of the blades, the edge 78 being discontinuous in its center, as at 85 to accommodate shank 32. The clamps 29 and 31, however, being so close to edge 78, assist 90 materially in supporting the bristles during cutting. The clamps also prevent movement of the bristles in a horizontal direction toward the axis of the broom as the blades descend, being tightly bound against the 95 body of bristles. The descent of the blades against the shoulders of the broom has a tendency to tilt the broom on the head block about a transverse horizontal axis, depressing the shanks and raising the foot. This 100 tendency is overcome by spacing the presser head 43 toward the center of the machine from the central recess 82 between the blades, thus giving it great leverage over the downward thrust of the blades. The force of the 105 presser head against the head block prevents shifting of the broom horizontally on surface 35, this holding function being assisted by contact between the shoulder edges of the clamps and the raised outer rim 110 of the head block. It will be noted that the anticlinal disposition of blade edges 83 balances the tendency each has, in cutting, to push the head of the broom toward the other: the cutting forces of the blades operate horizontally 115 against each other as well as downwardly. The trimming of the shoulders of the broom is simultaneous with the action of knife 58 in trimming the foot, both being accomplished in a single down stroke of die 120 plate 21.

125 The retaining posts 75 and 76 operate to center the foot of the broom in the machine for trimming. In feeding the machine, however, the head of the broom enters first. A centering post 86 (Figs. 1, 4 and 5) is pivoted on a vertical axis in the base plate at a point spaced somewhat toward the left end of the machine from the head block 36, this vertical axis lying in the axial vertical plane 130

of a broom properly centered for trimming. A vertical cylindrical bearing 87 is provided for the centering post and in which the latter rotates and slides piston like to a slight extent. Interposed between the bottom of the bearing and a shoulder formed on the centering post is a spring 88 which holds the post normally at the upper end of its short path of vertical movement, the post traversing a shelf 89 forming the bottom of the bearing and being shackled below the shelf by a washer and lock nuts 91. The upper end of the centering post is bifurcated, and between its bifurcations 92, and pivoted thereto by the horizontal pin 93, is the flattened outer end 94 of a cylindrical centering arm 95. The axis of pivot pin 93 is preferably normally in the horizontal plane of the axis of a broom centered in the machine. However, under the force of presser head 43 the head of a broom may be slightly compressed, lowering the broom axis. To accommodate this slight change in the position of the broom axis the centering post 86 is mounted for vertical reciprocation. It is customary to use enameled or painted clamps on clamp brooms. Frequently, due to the fresh condition of this enamel the clamps, under pressure, stick to the head block, or presser head, or to both. If this occurs with a given batch of brooms, lock nuts 91 can be lowered on the centering post, causing spring 88 to raise the latter and positioning the axis of pin 93 normally slightly higher than the axis of a broom lying loosely on the head block. Centering arm 95 fits snugly within the handle socket formed by the shanks 32 and 33 (Fig. 13) so that, after a broom is trimmed the release of the presser head allows spring 88 to force the lower clamp upwardly from surface 35, overcoming any adhesion between that surface and the painted lower clamp. The vertical movement of the centering post is, however, never more than enough to overcome this adhesion, while the vertical movement of the presser head is much greater: hence, when nuts 91 limit upward movement of the pin 93, arm 95 holds the broom head from rising further and the continued elevation of the presser head overcomes any adhesion between it and the painted upper clamp.

A small coiled spring 96 (Fig. 5) holds the inner free end of the centering arm normally uptilted, as shown in Fig. 1. In feeding the machine the shanks of the handle socket are slipped onto the bluntly pointed free end of the centering arm, (Fig. 13) this movement being limited by an annular stop ring 97 axially movable on the arm and fixed in any adjusted position by a set screw 98. During the trimming of a broom the pressure exerted on its clamps by presser head 43 and the head block 36 tends to bend the shanks 32 and 33 from each other to-

ward the positions indicated by the dotted lines 99 in Fig. 13. To prevent this distortion I provide integrally with stop 97, a sleeve 101 surrounding the centering arm 95 and spaced therefrom just enough to cause the extremities of the shanks to fit slidably and rotatably between the sleeve and arm.

Fig. 4 illustrates in plan view in dotted lines the initial position of the centering arm and broom in feeding and the final position in discharging the machine. The free end of the centering arm is swung forward as shown and the handle socket pushed upon it till limited by contact with stop ring 97. The foot of the broom is elevated above the top of the retaining post 75 and passed over that post till its rear edge bristles are stopped by the opposite, rear retaining post 76; by pressure of the hand the operator pushes the forward edge bristles over the top of post 75 and down along the inner wall thereof, confining the foot of the broom between these posts—the rear edge of the broom having dropped by gravity below the level of the tops of the retaining posts, the rotative relation between the arm and handle socket permitting this movement. The centering post and arm rotate about the vertical axis of the former as the foot of the broom is swung into position, and the centering arm turns about pivot pin 93 when the axis of the broom drops below the level of the tops of posts 75 and 76. To insure accurate centering of the broom in the machine there is provided near the rear inner corner of the head block (Figs. 1, 4, 5, and 7) a vertical detent 102 projecting rigidly from the base plate in a position to strike the rear edge of a broom and limit its inward swing about the axis of centering post 86. This detent is preferably mounted for adjustment forwardly and backwardly in the machine by means of a slotted bracket dovetailed into the top of the base plate and held stationary by a set screw: by this adjustment and the exchange of one head block for another the machine is conditioned to handle brooms of varying widths.

To prevent the catching of bristles on teeth 71 when the foot of a broom is fed into the machine, to permit quick centering of the broom before it is impaled on these teeth, and to eject it from the teeth after trimming, I position a guide plate 103 (Figs. 1, 4, 5 and 6) transversely of the machine just inwardly of the inner edge of surface 40 of the foot block. This guide plate normally occupies the dotted line position shown in Fig. 6, bridging the tips of teeth 71 so that the bristles may slide over them to the rear retaining post 76. It is, however, resiliently mounted, preferably comprising a leaf spring bolted by one end to portion 66 of the end block at the front of the machine, forming a loop 104 in front of the machine

and extending thence backwardly. The spring loop 104 permits it to bend under the force of presser foot 44 and presser bar 45 to the full line position of Figs. 5 and 6; 5 while upon release by these pressing members the spring loop elevates the guide plate, ejecting the foot of the broom from teeth 71.

A guide bar 105 (Figs. 1, 4, and 6) fixed at its rear end to the top of the front retaining post 75, projects forwardly and preferably downwardly therefrom to act 10 as a guide for the foot of a broom being fed into the machine.

Figs. 1, 3, 4, 5 and 6 illustrate a lower carriage 106 and an upper carriage 107 rigidly mounted respectively on the base plate and die plate and uniformly adjustable therein toward and from the centering post 86. Their uniform adjustment is made accurate (Figs. 20 3 and 4) by means of dowel pins 108 snugly engageable in mortises 109 before the fastening bolts 111 are set in their tapped holes 112. The transverse reach of the lower carriage comprises the foot block 37. These 25 carriages and the parts connected to them are adjustable to condition the machine for trimming brooms to various lengths: these parts comprise all the members herein described as operating on the foot of a broom.

30 In the operation of the machine, and considering a broom to be centered therein as above described, the die plate descends along the guide posts 23 and 24. The broom pressing devices carried by the die plate strike 35 the upper side of the broom in advance of the foot trimming knife 58 and the head trimming plates 81, presser head 43 binding the head of the broom against the head block 36, presser bar 45 pushing the medial 40 portion of the broom downwardly sufficiently to straighten the bristles in the central portion of the broom and leave the bristles of the upper and lower sides arched equally from each other, the present foot 44 driving its teeth 72 into the body of bristles, forcing the foot of the broom down upon the foot block 37, and impaling it upon the teeth 71 of the foot block. As seen in Figs. 4 and 5, the surface 38 of the 45 foot block is very narrow so that the bristles of the lower side of the broom, when arched downwardly by pressure of the bar 45, will not be bent so sharply as to break them. Normally the force of bar 45 arches 50 the lower bristles not only against the broom supporting surface 42 of the platen, but also causes them to rest likewise upon the inner or left hand edge portion of surface 40 of the foot block. Knife 58 and 55 blades 81 now strike the broom. As best seen in Fig. 6, the foot trimming knife strikes the rear edge bristles first and trims the foot of the broom progressively from back to front of the machine. The retain-

ing teeth 71 and 72 limit horizontal movement of the foot bristles under the edge 69 of the knife; and the hook 73 of that edge, being downturned, cuts the forward edge bristles 74 cleanly, preventing their being bent horizontally forward and unevenly 70 trimmed as to length or merely pinched without being cut. The hooks 84 at the lower outer extremities of the cutting edges 83 of the blades 81 strike the shoulders of the broom at the edges of the latter bending 75 the waste ends of the edge bristles inwardly from the position indicated in dotted lines at the left end of Fig. 8 to the full line position there shown, thereby forcing them against the body of waste ends to be cut and 80 holding them suitably for clean trimming. As the blades continue downward they shear off the waste ends of the bristles projecting from the shoulders of the broom, continuing their operation up to the handle socket. 85 The die plate now rises retracting the holding and cutting devices which it carries, and the broom is removed from the machine by lifting its foot above the level of the retaining post 75 and swinging the broom forwardly from the machine about the axis of centering post 86, being then withdrawn 90 from centering arm 95.

I claim:

1. In a broom trimming machine, the 95 combination with head and foot blocks comprising surfaces in a common plane adapted to support respectively the head and foot of a broom, of a platen between said blocks comprising a broom supporting surface 100 without said common plane.

2. In a broom trimming machine, the combination with elements comprising a set of broom supporting surfaces arcuately disposed in the direction of length of the bristles of a broom, of means for holding a broom against said surfaces, said means being movable toward and from said surfaces and disposed to contact with the ends and medial portions of the bristles of a broom. 105

3. In a broom trimming machine, the combination with members arranged in pairs for holding the head and foot of a broom to be trimmed, of a broom deflecting device movable against the broom between 115 the head and foot thereof and mounted in the machine to yield independently of said members.

4. In a broom trimming machine, the combination with head and foot blocks comprising surfaces in a common plane adapted to support respectively the head and foot of a broom to be trimmed, of a platen between said blocks comprising a surface offset with respect to said common plane and 120 adapted to support the medial portion of a broom, a die-plate reciprocable toward and from the blocks and platen, a presser head 125

- and a presser foot both carried by the die-plate and respectively opposed to said head and foot blocks, and a presser bar carried by the die-plate and opposed to the platen.
5. In a broom trimming machine, the combination with head and foot blocks comprising surfaces in a common plane adapted to support respectively the head and foot of a broom to be trimmed, of a platen between 65
10 said blocks comprising a surface offset with respect to said common plane and adapted to support the medial portion of a broom, a die-plate reciprocable toward and from the blocks and platen, devices opposed to the re- 70
15 spective blocks to hold the head and foot of a broom thereon, and a presser bar resiliently mounted on the die-plate and opposed to the platen to press a broom against the same.
20. In a broom trimming machine, the combination with a set of elements positioned to support a broom to be trimmed, of a die-plate reciprocable toward and from said elements, devices yieldingly carried by 75
25 the plate for holding a broom against said elements, and cutters mounted on the plate for simultaneously trimming the head and foot of a broom.
7. In a broom trimming machine, the combination with a set of broom supporting 80
30 elements, of a die-plate reciprocable toward and from the same, and cutters spacedly mounted on the plate for simultaneously trimming the head and foot of a broom sup- 85
35 ported on said elements.
8. In a broom trimming machine, the combination with broom supporting elements, of devices for holding a broom against the same, said elements being arcuately dis- 90
40 posed in the direction of length of the broom bristles and said devices being yieldably mounted for movement toward the elements and so arranged relatively to the elements as to hold in substantially straight condition 95
45 the bristles in the central portion of the broom and to arch from each other the bristles on opposite sides of said central bristles.
9. In a broom trimming machine, the combination with a set of broom supporting 100
50 elements adapted to contact with one flat side of a broom, of a series of devices each being positioned to contact with the other flat side of the broom in opposition to one of said elements to hold the broom against 105
55 the elements, said elements being arcuately disposed in the direction of length of the broom bristles and said devices being yieldably mounted for movement toward the elements to hold in substantially straight condition the bristles in the central portion of the broom and to arch from each other the bristles on opposite sides of said central bristles.
60. In a broom trimming machine, the combination with a foot block supporting ele- 110
65 ments comprising a foot block having a sharp edge, of a knife movable across said edge to trim a broom supported on the foot-block, and an end block spaced from the foot block to permit movement of the knife be- 115
70 tween said blocks and having a surface normally flush with the sharp edge of the foot-block and adapted to support the waste ends of bristles trimmed by the knife, said end block being yieldable in the direction of the cutting movement of the knife.
11. In a broom trimming machine, the combination with a base plate, of spaced foot and end blocks mounted thereon for support of a broom to be trimmed, a knife 120
75 reciprocable between the blocks and against the foot block to trim the foot of a broom, and means whereby said end block is re- 80
85 siliently mounted on the base plate to yield in the direction of the cutting movement of the knife.
12. In a broom trimming machine, the combination with a base plate, of a foot-block rigidly mounted thereon and having a sharp edge, an end block substantially co-extensive with the foot-block and spaced therefrom, parallel pivot arms one on each extremity of the end block, traversing the extremities of the foot block and coaxially pivoted to the base plate, springs holding 90
95 the end block normally spaced from the base plate with its upper surface substantially level with the sharp edge of the foot-block, and a knife reciprocable between said blocks to trim a broom supported by the blocks. 100
13. In a broom trimming machine, the combination of a foot-block adapted to support broom bristles laid across it, a knife movable across an edge of the foot-block to cut off the waste ends of such bristles, and means yieldable in the direction of the cutting movement of the knife for supporting said waste ends during the cutting operation. 105
14. In a broom trimming machine, the combination with a foot block forming a transverse support for the bristles of a broom to be trimmed, of a presser foot movable toward the block to hold the bristles against the latter, a series of spaced teeth 110
115 projecting toward the presser foot from the foot-block, and a knife movable across an edge of the foot-block to trim the bristles.
15. In a broom trimming machine, the combination with a foot-block forming a transverse support for the bristles of a broom to be trimmed, of a series of spaced teeth upstanding from the block and substantially co-extensive therewith, and a knife movable across an edge of the foot 120
125 block to trim the bristles.
16. In a broom trimming machine, the combination with a foot block forming a

- transverse support for the bristles of a broom to be trimmed, of a presser foot movable toward the block to hold the bristles against the latter, a series of spaced teeth 5 projecting toward the presser foot from the foot block, a series of spaced teeth projecting toward the foot block from the presser foot, and a knife movable across an edge of the foot block to trim the bristles.
- 10 17. In a broom trimming machine, the combination with a foot block forming a transverse support for the bristles of a broom to be trimmed, of a presser foot movable toward the block to hold the bristles 15 against the latter, a series of spaced teeth projecting toward the presser foot from the foot block, a series of spaced teeth, staggered with respect to the foot block teeth, projecting toward the foot block from the 20 presser foot, and a knife movable across an edge of the foot block to trim the bristles.
18. In a broom trimming machine, the combination with a foot block forming a transverse support for the bristles of a broom 25 to be trimmed, of a presser foot movable toward the block to hold the bristles against the latter, a series of spaced teeth projecting toward the presser foot from the foot block, a series of spaced teeth, staggered 30 with respect to the foot block teeth, projecting toward the foot block from the presser foot, all of said teeth being shorter than the thickness of the broom when pressed against the foot block, and a knife movable across 35 an edge of the foot block to trim the bristles.
19. In a broom trimming machine, the combination with a foot block forming a transverse support for the bristles of a 40 broom to be trimmed, of a knife having its cutting edge slanted with respect to the bristle supporting surface of the foot block and movable across an edge of the foot block to trim the broom, and means penetrating 45 the body of bristles at an angle to said surface to limit transverse movement of the bristles under the pressure of the knife.
20. In a broom trimming machine, the combination with a foot block, having a 50 broom supporting surface, of a knife movable across an edge of the block, to trim a broom held on said surface, and spaced teeth projecting from said surface of the block.
21. In a broom trimming machine, the combination with a base plate, of a lower 55 carriage mounted thereon, a die plate reciprocal toward and from the base plate, an upper carriage carried by the die plate, broom supporting elements mounted on the lower carriage, broom pressing devices carried by said upper carriage, said elements and devices coöperating to grip the foot of a broom to be trimmed, and a centering post mounted on the base plate independently of

the lower carriage and forming a stop for 65 the head of a broom; said carriages being adjustable on their respective plates toward and from said centering post.

22. In a broom trimming machine, the combination with a base plate, of means 70 mounted thereon forming a stop for the head of a broom, a foot block mounted on the base plate for support of the foot of a broom and having a sharp edge, a die-plate reciprocal toward and from the base plate, 75 and a knife carried by the die-plate and movable thereby across the sharp edge of the foot block to trim a broom, said foot block and knife being uniformly adjustable on their respective plates toward and from 80 said means.

23. In a broom trimming machine, the combination with a base plate, of means 85 thereon for fixedly positioning the head of a broom, a lower carriage mounted on the base plate, a die-plate reciprocal toward and from the base plate, an upper carriage carried by the die-plate, said carriages being uniformly adjustable on their respective plates toward and from said means, a foot 90 block mounted on the lower carriage and having a surface adapted to support the foot of a broom to be trimmed, an end block spaced from the foot block, yieldingly mounted on the lower carriage, and having 95 a surface normally flush with the broom supporting surface of the foot block adapted to support the waste ends to be trimmed from a broom, a presser foot carried by the upper carriage and movable toward the foot 100 block to hold a broom against the same, and a knife carried by the upper carriage and movable across an edge of the foot block and between the foot and end blocks to trim 105 a broom.

24. In a broom trimming machine, the combination with a base plate, of means 110 thereon for fixedly positioning the head of a broom, a lower carriage mounted on the base plate, a die plate reciprocal toward and from the base plate, an upper carriage carried by the die plate, said carriages being uniformly adjustable toward and from 115 said means, a foot block mounted on the lower carriage and having a surface adapted to support the foot of a broom to be trimmed, a presser foot carried by the upper carriage and movable toward the foot block to hold a broom against the same, a series of spaced teeth projecting toward the 120 presser bar from the foot block, and a series of spaced teeth which are staggered with respect to those of the foot block projecting toward the foot block from the presser foot.

25. In a broom trimming machine, the combination with a base plate, of means 125 thereon for fixedly positioning the head of

- a broom, a lower carriage mounted on the base plate, a die plate reciprocable toward and from the base plate, an upper carriage carried by the die plate, said carriages being uniformly adjustable toward and from said means, a foot block mounted on the lower carriage and having a surface adapted to support the foot of a broom to be trimmed, a presser foot carried by the upper carriage and movable toward the foot block to hold a broom against the same, spaced teeth projecting toward the presser bar from the foot block, spaced teeth projecting toward the foot block from the presser foot, and a knife carried by the upper carriage, having its edge slanted with respect to the broom supporting surface of the foot block and movable across an edge of the foot block to trim a broom.
- 20 26. In a broom trimming machine, the combination with a base plate, of means at one end thereof for fixedly positioning the head of a broom, a lower carriage mounted on the other end of the base-plate, broom supporting elements mounted on said lower carriage, a die plate reciprocable toward and from the base plate, an upper carriage carried on the die plate, and broom pressing devices carried by said upper carriage, one opposite each of said supporting elements, movable toward the elements to hold a broom against the latter, said elements being arcuately disposed in the direction of length of the broom bristles and said devices being yieldably mounted on the die plate to hold in substantially straight condition the bristles in the central portion of a broom and to arch from each other the bristles on opposite sides of said central portion, said upper and lower carriages being uniformly adjustable on their respective plates toward and from the broom head positioning means.
- 25 27. In a broom trimming machine, the combination with a base plate, and a die plate reciprocable toward and from the same; of a group of members for performing work upon a broom comprising elements mounted at one end of the base plate, and devices carried on the corresponding end of the die plate; a second group of work performing members, comprising elements mounted on the opposite end of the base plate, and devices carried on the adjacent end of the die plate; one of said groups being mounted for uniform adjustment of its elements and devices toward and from the other group.
- 30 28. In a broom trimming machine, the combination with a head block adapted to support flatwise the head of a broom to be trimmed and shaped in conformity with the shoulders of the broom, of a device for holding a broom head against the block, and a pair of shoulder trimming blades movable across the shaped edge of the block, slanting downward from their inner toward their outer ends, and pitched more sharply downward at their outer ends, said outer ends of the blades being positioned to trim the bristles at the opposite edges of the broom.
- 35 29. In a broom trimming machine, the combination with means for fixedly positioning the head of a clamp broom, of a pair of blades movable across said head for trimming simultaneously the shoulders of the broom, the edge of each of said blades being shaped to cut the shoulder bristles by pressure across the same in a direction angled with respect to the plane of the broom and from the edge of the broom toward the longitudinal axis thereof.
- 40 30. In a broom trimming machine, the combination with a fixed head block, of a die plate reciprocable toward and from the same, blades fixed on the die plate for trimming a broom supported on the head block, a presser head carried by the die plate and opposed to the head block to hold a broom upon the block, and mechanism for securing the presser head to the die plate whereby, during the cutting movement of the blades the presser head is resiliently pressed against a broom on the head block, said mechanism being adjustable to vary the pressure exerted by the presser head.
- 45 31. In a machine for trimming the shoulders of clamp brooms, said shoulders being defined by the edges of the clamps, the combination with means for holding the broom stationary, of blades movable across the edges of the clamps for cutting bristles held between the clamps and projecting therefrom.
- 50 32. In a machine for trimming the shoulders of clamp brooms, the combination with a head block adapted to support one side of a broom near the shoulder thereof, of a blade movable across a shoulder of the broom in a direction toward said block to trim said shoulder, and a presser head exerting pressure toward the block and against the opposite side of the broom at a point remote from said shoulder to prevent tilting of the broom during the cutting action of the blade.
- 55 33. In a machine for trimming a broom having a handle socket, the combination with broom gripping members, of an arm shaped to enter the handle socket and projecting toward said member, and a stop on the arm positioned to contact with the end of the socket wall to limit movement of the broom onto the arm, said stop being adjustable axially of the arm.
- 60 34. In a machine for trimming a clamp broom having separate clamp shanks defining a handle socket, of a head block for support of one side of the head of the broom,

a presser head movable against the opposite side of the broom to hold the latter against the block, an arm positioned to enter the handle socket, and means for preventing distortion of said shanks under the force of the head and block comprising a sleeve carried by the arm, spaced therefrom and shaped interiorly to receive the clamps and hold them against separation.

10 35. In a machine for trimming a broom having opposed head clamps and opposed shanks, one on each clamp, defining a handle socket, the combination with opposed members exerting pressure on the clamps to hold 15 the broom stationary, of a centering arm projecting toward said members and shaped to enter the handle socket, a stop on the arm positioned to contact with the end of the socket wall to limit movement of the shanks 20 onto the arm, and a sleeve fixedly supported by the stop, spaced therefrom, and shaped interiorly to receive said clamps and hold them against separation.

36. In a machine for trimming a clamp 25 broom having separate shanks defining a handle socket, the combination with elements for performing work upon a broom and exerting force thereon tending to separate said shanks, of an arm positioned to enter 30 the handle socket and shaped to substantially fill the same, a ring mounted on the arm for adjustment axially thereof and positioned to contact with the end of the socket wall to limit movement of the shanks onto 35 the arm, and a shank embracing sleeve mounted on the ring, projecting toward the free end of the arm and spaced from the arm sufficiently to receive between itself and said arm the free ends of the shanks.

40 37. In a machine for trimming a broom having a handle socket, the combination with a base plate, of a block fixed thereon for support of a broom, a centering post vertically pivoted in the base plate, a centering arm projecting laterally from the post and shaped to fit the socket of the broom and a detent upstanding rigidly from the base plate to limit pivotal movement of the broom about the axis of the centering 45 post.

50 38. In a machine for trimming a broom having a handle socket, the combination with a base plate, of a block fixed thereon for support of a broom, a centering post vertically pivoted in the base plate, a centering arm projecting laterally from the post and shaped to fit the socket of the broom, and a detent upstanding rigidly from the base plate to limit pivotal movement of the broom about the axis of the centering post, said detent being adjustable in a direction transverse to the axis of a broom positioned on the head block.

55 39. In a machine for trimming a broom

having a handle socket, the combination with a base plate, of a head block fixed thereon for support of a broom on its horizontal upper surface, a presser head reciprocable toward and from the head block to press a broom against the same and release it, a centering post vertically pivoted in the base plate near the head block and resiliently mounted for reciprocation in the direction of movement of the presser head, and a centering arm projecting laterally from the post and shaped to fit the socket of the broom.

60 40. In a machine for trimming a broom having a handle socket, the combination with a frame, and broom trimming members operatively mounted therein, of means for centering a broom with respect to said members, comprising a vertically pivoted centering post, a centering arm horizontally pivoted thereto and shaped to fit the socket of the broom, and a detent positioned to limit the movement of the broom about the axis of the centering post.

65 41. In a machine for trimming a broom having a handle socket, the combination with a frame, and broom trimming members operatively mounted therein, of means for centering a broom transversely and axially with respect to said members, comprising a vertically pivoted centering post, a centering arm horizontally pivoted thereto and shaped to fit the socket of the broom, a stop carried on said arm and positioned to limit movement of the broom onto the arm, and a detent positioned to limit movement of the broom about the axis of the centering post.

70 42. In a machine for operating upon brooms having handle sockets, the combination with a frame, of a centering post vertically pivoted therein, a centering arm horizontally pivoted to the post and shaped to fit said handle socket, and a spring interposed between the post and arm to normally hold the free end of the arm above the horizontal plane of its pivotal axis.

75 43. In a machine for operating upon brooms having handle sockets, the combination with a frame, of a centering post vertically pivoted therein, a centering arm horizontally pivoted to the post and shaped to fit said handle socket, and a spring interposed between the post and arm to normally hold the free end of the arm elevated above the horizontal, said spring being of insufficient strength to overcome the weight of a broom socketed upon the arm.

80 44. In a machine for operating upon a broom having longitudinally separated shanks projecting from its head and defining a handle socket, the combination with a frame, of a centering post pivoted therein and mounted to yield axially, a centering arm shaped to fit said handle socket and

125

pivoted to the post on an axis angled with respect to that of the post, and a sleeve rigidly carried by the centering arm and spaced therefrom to receive and closely overlie the 5 ends of said shanks.

45. In a broom trimming machine, the combination with a foot block, and teeth projecting therefrom, of means for guiding a broom across the tips of the teeth, comprising a guide plate yieldingly mounted and normally standing farther from the broom supporting surface of the block than said teeth.

46. In a broom trimming machine, the combination with an element having a broom supporting surface, a device movable toward and from said surface to press a broom thereagainst, and a series of teeth projecting toward the device from said element, of a guide plate substantially co-extensive with the series of teeth, yieldable in the direction of the broom pressing movement of said device, and, in the remote position of the device with respect to said element, standing between the teeth and the element.

47. In a broom trimming machine, the combination with a foot block having a broom supporting surface, a presser foot reciprocable toward and from said surface to press a broom against the same and thereafter release it, and teeth projecting from said surface toward the presser foot and adapted to impale a broom, of a guide plate 35 normally bridging the tips of the teeth and resiliently mounted in the machine to yield under the force of the presser foot when the broom is impaled and to thrust the broom from the teeth upon the releasing movement 40 of the presser foot.

48. In a broom trimming machine, the combination with a foot block having a broom supporting surface of sufficient length to receive flatwise the full width of the foot 45 of a broom, of a pair of bristle retaining posts projecting rigidly one from each end thereof a distance greater than the normal thickness of the foot of an untrimmed broom, and a presser foot movable toward 50 said surface in the direction of extent of said posts to compress the bristles between itself and the foot block and confine them between said posts.

49. In a broom trimming machine, the 55 combination with a foot block having a broom supporting surface, of a pair of bristle retaining posts projecting one from each end thereof a distance greater than the normal thickness of the foot of an untrimmed broom, a presser foot reciprocable toward said surface from a position remotely beyond the free ends of the posts to compress the foot of a broom and release the same, and a guide bar projecting from

the free end of one of said posts in a direction opposite to said foot block.

50. In a broom trimming machine, the combination with a base plate, of a foot block mounted thereon having a surface adapted to support the foot of a broom to 70 be trimmed, a pair of retaining posts projecting from said surface one at each end thereof, and means pivoted in the base plate on an axis at right angles to said surface and remote therefrom for centering the head 75 of a broom with respect to said foot block and posts.

51. In a broom trimming machine, the combination of a base plate; broom supporting elements mounted thereon comprising a foot block having a broom supporting surface extending transversely of the base plate, and a pair of retaining posts projecting from said surface, one at each end thereof; a die plate reciprocable toward and from 80 the base plate; broom gripping and cutting devices carried thereby for coöperation with said elements; and means for guiding a broom edgewise between said elements and devices during the separation thereof and 85 centering it with respect to them, comprising a centering post vertically pivoted in the base plate remote from the foot block, a centering arm horizontally pivoted to the centering post and shaped to slidably enter 90 a handle socket axially positioned on the broom to be trimmed and to permit rotative movement of the broom about the longitudinal axis of the arm, and a guide bar projecting outwardly of one of said retaining 95 posts from the free end thereof.

52. In a broom trimming machine, the combination of a base plate; broom supporting elements mounted thereon comprising a foot block having a broom supporting 105 surface extending transversely of the base plate, a pair of retaining posts projecting from said surface, one at each end thereof, and broom impaling teeth also projecting from said surface; a die plate reciprocable 110 toward and from the base plate; broom gripping and cutting devices carried thereby for coöperation with said elements; and means for guiding edgewise between said elements and devices, during their separation, and centering with respect to the same a broom having a handle socket projecting 115 axially from its head, comprising a centering post vertically pivoted in the base plate remote from the foot block, a centering arm horizontally pivoted to the centering post shaped to slidably fit within said socket and permit rotative movement of the socket about the longitudinal axis of the arm, a guide bar projecting outwardly of one of said 120 retaining posts from the free end thereof,

and a guide plate substantially co-extensive with said foot block, bridging the tips of 125

said teeth, and resiliently mounted for reciprocation between a position above the teeth and one in the plane of said surface of the foot block.

5 53. The method of trimming brooms, which consists in arching from each other the bristles at opposite sides of the broom,

10 maintaining the central bristles substantially straight, holding the arched and straight bristles against movement, and producing a transversely concave broom end by cutting transversely across the bristles so held.

GEORGE W. MANNING.
